[57] **CLAIM**

The ornamental design for a bag holder, as shown and described.

DESCRIPTION

FIG. 1 represents an isometric view of the bag holder showing our new design;

FIG. 2 is a rear elevational view thereof;

FIG. 3 is a front elevational view thereof;

FIG. 4 is a top plan view thereof;

FIG. 5 is a bottom plan view thereof; and,

FIG. 6 is a side elevational view thereof, the opposite side elevational view being identical thereto.
